UNITED STATES PATENT OFFICE.

WALTER L. NOWELL, OF COLLINGSWOOD, NEW JERSEY.

ELECTROMAGNETIC RETARDED SWITCH.

Application filed July 30, 1926. Serial No. 125,890.

This invention relates to electro-magnetic relays or switches and more particularly to a slow acting switch of this character.

In certain electrical circuits, such as are found in signaling and telephone systems, conditions are often met which require that a relay or switch be retarded in its operation in order to allow some other device sufficient time in which to perform its function.

10 The object of the invention is to provide a device adapted to open one circuit at the end of a predetermined period of time after another circuit has been closed and to so design the device that the length of such period 15 of time may be regulated.

Another object of the invention is to provide a device in which the elapsed time between the closing of one circuit and the breaking of another circuit is dependent upon 20 the speed of travel of a moving body and in which this moving body is positively started upon its journey.

These objects, and other advantageous ends which will be described hereinafter, I attain 25 in the following manner, reference being had to the accompanying drawings in which—

Figure 1 is a side elevation, partly in section, of a time switch made in accordance with my invention,

30 Figure 2 a like view showing the time switch in another position,

Figure 3 a plan view of the time switch, Figure 4 a section on line 4—4 of Figure 1, Figure 5 a section on line 5—5 of Figure

35 3, certain of the parts being shown in full.

Referring now more in detail to the drawings, my improved switch is provided with a support 27 which is made up of end members 28 and a core casing 29 connecting the 40 members. A coil 30 is wound on casing 29 and with a core, to be later described, mounted in the casing forms an electro-magnet. A tube 31 is tiltably mounted on support 27 by providing trunnions 32 on the sides of the tube and mounting them in bearings 33 fixed to end member 28. Trunnions 32 are disposed nearer the left end of tube 31 to cause the tube to be normally tilted by its weight to the right, when viewed from Figure 1. An armature 34, carried by a bracket 35 depending from tube 31, when attracted by the electro-magnet tilts the tube to the left as shown in Figure 2. The armature is secured and adjusted on the bracket by a threaded rod 36 and nut 37 which are made of magnetic

metal. A magnetic stop 38 is adjustably mounted on the end of rod 36 and is disposed adjacent the left open end 39 of tube 31. A ball 40 of magnetic metal at the right end 41 of the tube will, when the tube is tilted to the left, roll toward the left end 39 and come to rest against magnetic stop 38 which will attract and hold the ball in position. To give the ball a starting movement when the tube is tilted, I preferably provide a rod 42 with a bent end 43 so that its inner face will be at an angle to the direction of upward movement of the ball when the tube is tilted. This bent end will force the ball down the tube. The ball upon reaching the left end 39 of the tube will engage and swing an arm 44 of a switch to cause it to open. The arm extends part way into the tube through a slot 45 into the path of the ball.

The switch includes a lever 46 fixed with 75 a shaft 47 mounted in a bearing 48 adjustably mounted on end member 28. Arm 44 is fixed with shaft 47 and thereby swings lever 46. One end of lever 46 carries an electrode 49 and the other end of the lever carries an 80 adjustable counterweight 50. This counterweight nearly balances the weight of the electrode and in this manner assists arm 44 in swinging the lever to raise the electrode. The electrode, when closing the switch, dips 85 into mercury 51 in a cup 52 which has a terminal 53. The mercury cup may be mounted on end members 28 of the support 27 in any suitable manner.

Bearing 48 is mounted for up and down 90 adjustment so that lever 46 may be adjusted to such position that its electrode 49 will be a safe circuit breaking distance from the mercury when the switch is open. This up and down adjustment may be brought about 95 by pivotally mounting an extension 54 on bearing 48, on trunnion bearing 33 and adjusting the free end of extension 54 by a screw 55 threaded in bearing 33.

The degree of tilt of tube 31 is limited by a 100 stop 56 which is engaged by armature 34, and is partly of magnetic metal and partly of non-magnetic metal, as shown at 57, to prevent armature 34 from being magnetically held by stop 56 when coil 30 is de-energized. This stop is adjustably mounted in core casing 29 and is adjusted by a screw 58 threaded in a bracket 59 secured to end member 28. Adjusting the stop varies the tilt of tube 31. This varies the time in which ball 40 will roll 105 110

down the tilted tube to actuate arm 44 and raise the electrode 49 out of mercury 51 to break the circuit. Stop 56 also serves as a metallic core and with coil 30 forms the electro-magnet which attracts armature 34.

Rod 42 with its bent end 43 is especially adapted for use when the degree of tilt of tube 31 is small so as to give the ball a start when the tube is tilted. When the degree of tilt is large, rod 42 may be omitted. The end 41 of the tube is then peened inwardly to partly close the tube and prevent the ball from rolling out of the tube. Closing up the end of the tube in this manner also serves to prevent the ball from rolling out of the tube in case rod 42 should become accidentally bent out of position or broken.

It will be understood that my time retarding switch is disposed in and designed to be actuated by an elevator circuit which is closed when the elevator is moving and open when the elevator is at rest.

The operation is as follows: When the elevator circuit is closed the electro-magnet is energized. It attracts armature 34 and keeps tube 31 tilted to the left. Ball 40 will be at the left end of the tube resting upon arm 44 and its weight will hold the arm down and consequently hold electrode 49 out of the mercury in cup 52 and the retarding switch will be idle.

When the elevator stops and the elevator circuit is broken, the electro-magnet is de-energized and armature 34 released. Tube 31 then tilts to the right by gravity, ball 40 rolls downward until it contacts with arm 42, arm 44 swings upward and, being fixed to the shaft 47, swings the heel end of lever 46 upward and the electrode 49, carried by the other end of the lever, downward and into the mercury, thereby closing the switch.

When the elevator is started and the elevator circuit closed, the electro-magnet is again energized and the operation is reversed.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A device of the character described including a support; an electro-magnet on the support; a tube pivoted on the support; an armature carried by the tube and adapted to be attracted by the magnet to tilt the tube; a switch on the support having a part extending into the tube when tilted, means adapted to travel down the tilted tube to engage and move said part and open the switch,

and a fixed member adapted to abut said means when the tube is tilted.

2. A device of the character described including a support; an electro-magnet on the support; a tube pivoted on the support; an armature carried by the tube and adapted to be attracted by the magnet to tilt the tube; a switch including a movable electrode; means including an arm connected with the electrode and extending into the tube when tilted, means adapted to travel in the tube when tilted and engage the arm to move the electrode and open the switch, and a fixed member adapted to abut said means when the tube is tilted.

3. A device of the character described including a support; an electro-magnet on the support; a tube pivoted on the support; an armature carried by the tube and adapted to be attracted by the magnet to tilt the tube; a switch including a swingable electrode; means including an arm fixed with the electrode extending into the tube, and a ball adapted to travel down the tilted tube to engage and move the arm and swing the electrode to open the switch, and a fixed member adapted to abut the ball when the tube is tilted.

4. A device of the character described including a support; an electro-magnet on the support; a tube pivoted on the support; an armature carried by the tube and adapted to be attracted by the magnet to tilt the tube; a mercury containing cup; a lever; an electrode carried by the lever and adapted to dip into the mercury in the cup; an arm connected with said lever and extending into the tube, and a ball adapted to travel down the tilted tube to engage and move the arm and swing the electrode from the cup.

5. A device of the character described including a support; an electro-magnet on the support; a tube pivoted on the support; an armature carried by the tube and adapted to be attracted by the magnet to tilt the tube; a mercury containing cup; a lever; an electrode carried by one end of the lever and adapted to dip into the mercury in the cup; a counter-weight on the other end of the lever; an arm fixed with the lever and extending into the tube, and a ball adapted to travel down the tilted tube to engage and move the arm and swing the electrode from the cup.

6. A device of the character described including a support; an electro-magnet on the support; a tube pivoted on the support; an armature carried by the tube and adapted to be attracted by the magnet to tilt the tube; a bearing adjustably mounted on the support; a lever mounted in the bearing; a mercury containing cup; an electrode carried by the lever and adapted to dip into the mercury in the cup; an arm fixed with the lever and extending into the tube when tilted, and a

ball adapted to travel down the tilted tube to engage and move the arm and raise the electrode from the cup.

7. A device of the character described including a support; an electro-magnet on the support; a tube pivoted on the support; an armature carried by the tube and adapted to be attracted by the magnet to tilt the tube; a bearing mounted for swingable adjustment

- 10 on the support; a lever mounted in the bearing; a mercury containing cup; an electrode carried by the lever, and adapted to dip into the mercury in the cup; an arm fixed with the lever and adapted to extend into the tube when tilted, and a ball adapted to travel down the tilted tube to engage and move the arm and raise the electrode from the cup.

- 15 8. A device of the character described including a support; an electro-magnet on the support; a tube pivoted on the support; an armature carried by the tube and adapted to be attracted by the magnet to tilt the tube; an adjustable core in the magnet adapted to be engaged by the armature to limit the tilting

- 20 movement of the tube; a switch mounted on the support and having a part extending into the tube when tilted, and a ball adapted to travel down the tilted tube to engage and move the part and open the switch.

- 25 9. A device of the character described including a support; an electro-magnet on the support; a tube pivoted on the support; an armature carried by the tube adapted to be attracted by the magnet to tilt the tube; a

- 30 35 magnetic stop connected with the armature and disposed at one end of the tube; a switch

mounted on the support and having a part extending into the tube, and a ball adapted to travel down the tilted tube to engage and move the part and open the switch and to be 40 attracted and held in switch opening position by the magnetic stop.

10. A device of the character described including a support; an electro-magnet on the support; a tube pivoted on the support; an 45 armature carried by the tube and adapted to be attracted by the magnet to tilt the tube; a switch mounted on the support and having a part extending into one end of the tube; a ball adapted to roll down the tilted tube to 50 engage and move the part and open the switch, and a fixed member having a face disposed at the other end of the tube at an angle to the direction of swinging movement of said end of the tube, whereby the ball will 55 engage and be moved by the fixed member when the tube is tilted.

11. A device of the character described including a support; an electro-magnet on the support; a tube pivoted on the support; an 60 armature carried by the tube and adapted to be attracted by the magnet to tilt the tube; a switch mounted on the support and having a part extending into one end of the tube; a ball adapted to roll down the tilted tube to 65 engage and move the part and open the switch, and means at the other end of the tube adapted to engage and move the ball when the tube is tilted.

In testimony whereof I have signed my 70 name to this specification.

WALTER L. NOWELL.
